SHELF EDGE SIGN ASSEMBLY

James Edward Howard, North Miami, Fla.

Application June 15, 1956, Serial No. 591,642

4 Claims. (Cl. 40—10)

This invention relates to improved shelf-edge sign assemblies which facilitate exhibit of and changing of price cards and the like.

The primary object of the invention is to provide more practical and efficient devices of this kind which exhibit cards in a more readable manner, which are simple in construction, and are composed of a small number of simple and easily assembled parts, which are readily separable for changing cards.

Another object of the invention is to provide devices of this kind which have card holders which are separably mounted on shelf edge mounted strips, and transparent covers which are separably mounted on the card holders for changing cards, the card holders and the covers being removable as units from the strips.

Another object of the invention is to provide shelf edge sign assemblies of the character indicated, which can be made in attractive, rugged, and serviceable forms at relatively low cost, are easily installed, and are highly satisfactory for the purpose intended.

These together with other objects and advantages which will become apparent reside in the details of construction and operation as more fully hereinafter described and claimed, reference being had to the accompanying drawings forming a part hereof, wherein like numerals refer to like parts throughout the several views, and in which:

Figure 1 is a fragmentary perspective view of a shelf edge sign assembly of the present invention, mounted on the forward edge a shelf;

Figure 2 is an enlarged vertical transverse sectional view taken substantially on line 2—2 of Figure 1;

Figure 3 is an exploded perspective view of the novel shelf edge sign assembly of Figures 1 and 2; and

Figure 4 is a vertical transverse sectional view, on a reduced scale, similar to Figure 2, showing a modified form of shelf edge sign assembly.

Referring to the drawings in detail, and first to Figures 1 to 3, indicated generally at 10 is a shelf having an upper surface 12, and a forward edge 14. Secured on the edge 14 of the shelf is a shelf edge sign assembly, indicated generally at 16, of the present invention.

The shelf edge sign assembly 16 comprises an elongated channel-shaped mounting strip, indicated generally at 18, which extends along the shelf edge 14, and which includes a forwardly declining flat web 20 having upper and lower longitudinally extending arcuate convex beads 22 and 24 which are continuations of the web 20, as clearly shown in Figure 2, said beads terminating in rearwardly extending and rearwardly converging flat upper and lower flanges 26 and 28, respectively, terminating at their rear edges in coplanar vertical abutment flanges 30 and 32, respectively, which are engageable against the shelf edge 14. The web 20 of the strip 18 has in its forward side a longitudinally extending groove 34, see Figure 2, traversed by suitable fastening elements, such as wood screws 36 which are threaded into the shelf edge 14 between the abutment flanges 30 and 32.

Indicated generally at 38 is an elongated card carrier

2

which comprises a flat web 40 having on its upper and lower edges rearwardly extending resilient arcuate concave clip flanges 42 and 44 which are removably engageable over the upper and lower beads 22 and 24 of the 5 mounting strip 18. The web 40 has secured on its forward side 46 a card holder 48 which comprises a flat plate 49, which is registered with the web 40, and is spaced forwardly from and secured to the web 40 by vertically spaced longitudinal ribs 50, as by means of 10 spot welding. The plate 49 of the card holder 48 includes narrow upper and lower forwardly offset edge portions 52 and 54 extending angularly from the plate 49.

Indicated generally at 56 is a card, of any suitable material, having thereon information 58 identifying the kind of goods, retail price, quantity purchased, whether or not the material is stocked, the source of manufacture, and cost of the item, for example, for facilitating inventory procedures. The card 56 is positioned on the 15 forward side of the plate 49 of the card holder 48.

Indicated generally at 60 is a transparent cover having a flat web 62 having on its upper and lower edges upper and lower hook flanges 64 and 66 removably engageable over the edge portions 52 and 54, respectively, of the 20 card holder 48 to hold the card 56 in place thereon.

The cover 60 can be readily removed for exchanging cards in the event the goods on the shelf 10 are changed, and the carrier 38 together with the card and the cover, can be removed as a unit, when desired, from the strip 25 18.

In the modified form of the invention shown in Figure 4, the mounting strip 18' includes a flat web 20' terminating at its upper and lower edges in convex beads 22' and 24', respectively, which continue as rearwardly converging upper and lower flanges 26' and 28', respectively, which terminate in coplanar, vertically spaced abutment flanges 30' and 32', respectively. The forward side of the web 20' has therein a longitudinally extending groove 34', traversed by suitable fastening elements 36', as in 30 the form of Figures 1 to 3. The strip 18' of Figure 4 is susceptible of being produced by extrusion methods, for example, whereas the strip 18 of Figures 1 to 3 is of sheet material and is preferably formed by means of bending, for example.

Indicated generally at 56' is a card positioned on the forward surface of the web 20' of the strip 18'. Removably secured in overlying relationship to the card 56' is a transparent cover, indicated generally at 60', which comprises a transparent flat web 62' and arcuate 45 concave longitudinally extending clip flanges 64' and 66' on the upper and lower edges thereof and engaged over the beads 22' and 24', respectively. The form of the invention of Figure 4 eliminates the card holder 38 of the form of the invention of Figures 1 through 3.

It will be noted that the upper flanges 26 and 26' of the clips 18 and 18' are shorter than the lower flanges 28 and 28', so that the cards are displayed in highly 50 readable rearwardly inclined positions.

The foregoing is considered as illustrative only of the 55 principles of the invention. Since numerous modifications and changes will readily occur to those skilled in the art, it is not desired to limit the invention to the exact construction and operation shown and described, and accordingly all suitable modifications and equivalents may be resorted to, as fall within the scope of the appended 60 claims.

What is claimed is:

1. A shelf edge sign assembly comprising an elongated channel-shaped mounting strip comprising a vertical web having upper and lower edges, convex beads on and extending along said upper and lower edges and extending rearwardly from said web, said beads terminating in rear-

wardly extending and rearwardly converging upper and lower flanges having rear ends, vertically spaced vertical coplanar abutment flanges on the rear ends of said flanges and engageable with a shelf edge, fastening means for securing said strip to a shelf edge, and card holding means having upper and lower longitudinal concave clip flanges removably engaged over said upper and lower beads of the mounting strip.

2. A shelf edge sign assembly comprising an elongated channel-shaped mounting strip comprising a vertical web having upper and lower edges, convex beads on and extending along said upper and lower edges and extending rearwardly from said web, said beads terminating in rearwardly extending and rearwardly converging upper and lower flanges having rear ends, vertically spaced vertical coplanar abutment flanges on the rear ends of said flanges and engageable with a shelf edge, fastening means for securing said strip to a shelf edge, and card holding means having upper and lower longitudinal concave clip flanges removably engaged over said upper and lower beads of the mounting strip, said upper strip flanges being shorter than said lower strip flanges whereby said web of the strip is positioned at a rearwardly inclined angle.

3. A shelf edge sign assembly according to claim 1, wherein said card holding means comprises a card carrier comprising a flat vertical web having upper and lower edges having said concave clip flanges thereon, the web of the

5 card carrier having a forward side, a card holder secured to said forward side, said card holder comprising a flat vertical plate having upper and lower edges, forwardly offset edge portions on the upper and lower edges of the 10 card holder plate, said flat plate having a forward side, a card engaged with the forward side of the plate between said offset edge portions, and a cover comprising a transparent flat web having upper and lower edges, and hook flanges on the upper and lower edges of the cover plate removably engaged over the offset edge portions of the card holder and holding the card in place.

4. A shelf edge sign assembly according to claim 1 wherein said card holding means comprises a transparent plate having upper and lower edges having convex clip flanges thereon removably engaged over the concave beads of the mounting strip.
